UNITED STATES PATENT OFFICE.

CAROLYN EDWARD CRUMP, OF WASHINGTON, DISTRICT OF COLUMBIA.

SAFETY-ELEVATOR.

No. 799,834.

Specification of Letters Patent.

Patented Sept. 19, 1905.

Application filed November 30, 1904. Serial No. 234,951.

To all whom it may concern:

Be it known that I, CAROLYN EDWARD CRUMP, a citizen of the United States, residing at Washington, District of Columbia, have 5 invented certain new and useful Improvements in Safety-Elevators, of which the following is a specification.

Elevators are generally constructed to carry a given load with safety, and any excess there- 10 of within certain limits not only endangers the working parts of the lifting mechanism, but not unfrequently strains the same and lessens the period of its usefulness.

This invention has for its object to prevent 15 the working of an elevator when overloaded, to lock the same in its shaft, and to relieve the hoisting mechanism of the extra strain due to the excess of the load.

For a full description of the invention and 20 the merits thereof and also to acquire a knowledge of the details of construction of the means for effecting the result reference is to be had to the following description and accompanying drawings.

25 Figure 1 is a view in elevation of an elevator embodying the invention, the lower portion of the car being in section. Fig. 2 is a view similar to Fig. 1, showing the relation of the parts when the car is overloaded and 30 locked to the guides of the shaft. Fig. 3 is a horizontal section on the line $\alpha\alpha$ of Fig. 1. Fig. 4 is a detail view of the guide mechanism between the car and the movable or false platform.

35 Corresponding and like parts are referred to in the following description and indicated in all the views of the drawings by the same reference characters.

The car 1, which may be of any pattern or 40 make, is adapted to be operated by any suitable hoisting mechanism and is directed in its vertical movements by ways 2 at opposite sides of the shaft in the well-known manner.

Toothed bars 3 are attached to the ways 2, 45 and lock-bolts 4 are adapted to engage with the teeth thereof and hold the car in suspension under abnormal conditions. The lock-bolts 4 are spring-actuated and are adapted to be shot outward when relieved from restraint, 50 so as to engage with the teeth of the bars 3 and support the car in the shaft. By preference the lock-bolts 4 are mounted in openings 5 of the bottom 6 and are adapted to be pressed outward by means of coil-springs 7. Cords 8 or 55 like flexible connections are interposed be-

tween the lock-bolts 4 and the movable or false platform 9 and pass around guide-pulleys 10. Under normal conditions the platform 9 is supported a distance above the bottom 6 and the lock-bolts 4 are held re- 60 stricted against the tension of the springs 7. In the event of the car becoming overloaded the platform 9 is pressed downward, and the lock-bolts 4 being relieved of restraint are shot outward by the springs 7 and engage 65 with the teeth of the bars 3 and hold the car in suspension.

The false platform 9 is yieldably mounted upon the bottom or main platform 6 and is directed in its vertical movements by suitable 70 guides, which, as shown, consist of toothed bars 11 and correspondingly-toothed wheels 12, the latter being mounted in brackets 13, secured to the platform 9. There are four toothed bars 11, each being located near a 75 corner of the car. The toothed wheels 12 are constructed so as to embrace opposite sides of the toothed portion of the bars 11, so as to prevent lateral displacement of the platform 9. The teeth of the parts 11 and 12 are of 80 **V** form, thereby permitting of their free engagement and disengagement in each direction as the platform 9 moves up and down. As shown, a spring 14 is interposed between the platforms 6 and 9 and is preferably ar- 85 ranged at a central point and is connected at its ends to each by suitable attaching means. A housing 15 incloses the spring 14 and is connected at its upper end with the platform 9. Webs or braces 16 radiate from the hous- 90 ing 15 and stiffen and strengthen the platform 9. The flexible connections 8 pass upward through the spring 14 and housing 15 and are connected at their upper ends to the platform 9 in any determinate way. The strength of 95 the spring 14 is such as to sustain a given load and to yield when the load is exceeded, thereby permitting the connections 8 to slacken and the springs 7 to come into play and shoot the lock-bolts 4 into engagement with 100 the toothed bars 3 and lock the car or elevator in its shaft, thereby preventing strain of the hoisting mechanism and endangering the lives of passengers. A signal is combined with the elevator and is preferably of the 105 electric type and may consist of either an audi- 110 ble or visual device, or both. The signal is indicated at 17 and may comprise a red light, an alarm-bell, and an indicator. The electric wires 18 extend from the signal 17 and termi-

nate in contacts 19 and 20, which are normally separated and which are brought into engagement upon descent of the platform 9 when overloaded, thereby completing the alarm-
5 circuit and giving warning of impending danger by overload of the car. The electric contacts 20 are carried by the platform 9, whereas the contacts 19 are attached to the bottom of platform 6.

- 10 The upward movement of the platform 9 may be limited by any means, and for this purpose chains 21 are employed and are connected at their upper ends to said platform 9 and at their lower ends to the bottom or lower
15 platform 6. It is contemplated to regulate the tension of the spring 14, and for this purpose a set-screw 22 is threaded into the bottom 6, and its upper end engages with a plate 23, upon which the lower end of the spring 14
20 rests. It being remembered that the platform 9 is limited in its upward movement, a turning of the set-screw 22 to compress the spring 14 more or less results in varying its resistance to the load imposed thereon. In other
25 words, the platform being limited in its upward movement by means of the chains 21 the spring 14 is compressed more or less by turning the set-screw 22, with the result that its tension is varied and may be regulated to
30 support any determinate load.

Having thus described the invention, what is claimed as new is—

1. In an elevator, the combination of the car, means carried by the car for locking it in
35 its shaft, a yieldable platform for receiving the load, and connections between the yield-

able platform and locking means to normally hold the latter in restraint.

2. In an elevator, the combination of a car, locking means carried by the car for securing 40 it in its shaft, and a yieldable platform for receiving the load and adapted to admit of actuation of the locking means under abnormal conditions for holding the car in fixed position.

45

3. In an elevator, the combination of a car, automatic locking means carried thereby for securing the car in its shaft, and a yieldable platform for sustaining the load and adapted to control the locking means, substantially as 50 set forth.

4. In an elevator, the combination of a car, spring-actuated lock-bolts, a yieldable platform, and positive connections between said platform and lock-bolts for holding the latter 55 in restraint under normal conditions.

5. In an elevator, the combination of a car, oppositely-disposed spring-actuated lock-bolts, a movable platform, a spring interposed between said platform and the bottom of the 60 car for normally supporting the platform, a housing inclosing said spring, and flexible connections between the platform and lock-bolts, the latter being normally held out of action and adapted to be shot outward upon descent of the platform by an excess of load. 65

In testimony whereof I affix my signature in presence of two witnesses.

CAROLYN EDWARD CRUMP. [L. s.]
